UNITED STATES PATENT OFFICE.

MICHAEL PARIDON, OF BARBERTON, OHIO, ASSIGNOR TO THE DIAMOND MATCH COMPANY, OF CHICAGO, ILLINOIS, A CORPORATION OF ILLINOIS.

SPLINT-FEEDING MECHANISM FOR MATCH-MACHINES.

1,348,181.

Specification of Letters Patent.

Patented Aug. 3, 1920.

Application filed March 29, 1919. Serial No. 286,183.

To all whom it may concern:

Be it known that I, MICHAEL PARIDON, a citizen of the United States, and resident of Barberton, in the county of Summit and 5 State of Ohio, have invented certain new and useful Improvements in Splint-Feeding Mechanism for Match-Machines, of which the following is a specification.

This invention relates to that class of 10 match making machines in which successive rows of splints are delivered from a splint-supply hopper to a setting mechanism and thereby inserted into a traveling carrier which transports the splints through the 15 dipping and drying paths.

As heretofore constructed the splint-supply hopper comprised an upper stationary magazine section which was loaded with approximately parallel splints, and a lower 20 movable section into which the splints were progressively delivered from the upper section; said lower section being slidably fitted to suitable end guides on the main frame and being rapidly reciprocable directly 25 above and transversely of the setting mechanism in order to agitate the contained splints and promote their descent toward and upon such mechanism.

The operation of filling the upper section 30 with parallel splints is a difficult one; the usual practice being to arrange the splints in a portable tray by means of a splint assembling machine, then carry the filled tray to the match machine, and then transfer the 35 splints from the tray to the upper section of the hopper. Moreover, the accurate feeding of the relatively large mass of splints from the stationary to the movable section is uncertain, as, in the absence of special 40 guide devices, some of the splints frequently become awry during their descent and interfere with the orderly passage of the splints to and through the movable section, thus preventing the uniform delivery 45 of the splints to the setting mechanism.

According to my invention, I dispense with the upper stationary hopper section, and use in lieu thereof two splint-feeding structures which respectively lead to and 50 overhang the top of the movable section from opposite ends of the latter, in such a manner as to insure the orderly delivery of the splints, in divided quantities, to and throughout the length of the section.

55 The invention comprises also various

novel features of construction and combinations of parts which will be hereinafter described and claimed.

In the drawings—

Figure 1 is an elevation of a portion of 60 a match making machine embodying the principle of my invention.

Fig. 2 is a transverse vertical section, enlarged, through a stationary member constituting the inner ends of the inclined 65 trough structures, as on the line 2—2 of Fig. 1.

Fig. 3 is a similar section through one of 70 said structures, as on the line 3—3 of Fig. 1, the structure being shown as supplied with splints.

Fig. 4 is a sectional elevation of a portion 75 of the match making machine and the inner or delivery portions of the trough structures.

Referring to the drawings, 10 designates a part of the framework of a match making machine; 11 a part of a perforated match-carrier; 12 a reciprocating hopper section, and 13 a grooved setting head, which, reciprocating directly beneath the said section and toward and from the carrier, receives the splints from the section and inserts them row by row into the opposing 80 perforations of the carrier. 85

The hopper section is slidably fitted to suitable end guides 14 on the main frame, one end of said section being loosely connected to a bar 15 which is provided with a stud or roll 16 in operative engagement 90 with a peripheral cam 17 on a suitably-disposed stud shaft 18. This shaft bears a gear-wheel 19 in mesh with a gear 20 on a lower driven shaft 21, and hence a rapid vibratory motion is transmitted to the 95 hopper section in a manner to jar and agitate the contained splints and promote their descent toward and upon the setting head.

Instead of the stationary hopper section 100 heretofore employed to supply the lower reciprocative section with splints, I have devised the following simple and effective mechanism:

Overhanging the vibratory section, hereinafter termed a hopper, are two splint feeding chambers 22 comprising, in the present instance, the delivery portions of two splint guiding troughs 23 which incline upwardly 105 in opposite directions from the respective 110

ends of the hopper to suitable sources of splint supply. Each chamber overhangs substantially one half of the length of the hopper 12 and hence separate quantities of splints are delivered from the respective troughs 23 and uniformly distributed along the hopper. The sides of the chambers 22 are constituted by the enlarged end portions of the sides 24 of the troughs, which portions, together with the bottoms 25 of the respective troughs, are gradually curved or inclined downwardly toward the ends of the hopper, as at 26, in order to provide expanded passages for the splints as they are delivered to the respective chambers. The sides of each chamber are connected by transverse brace rods 27. The adjacent ends of the two chambers are formed by a stationary V-shaped member 28 which overhangs the hopper, the extremities of the respective sides slidably embracing said member. This member is affixed to a lateral bracket 29 on the inner side of a suitably disposed supporting bar 30 which is secured at its ends to brackets 31 on the main frame. The brackets 31 are provided at their upper portions with inward extensions 32 which underlie the inclined bottoms of the troughs adjacent the respective ends of the hopper, and are provided with guide portions 33 which slidably receive and support the channeled lower ends of guide brackets 34 depending from the respective troughs, whereby said troughs have capacity for longitudinal vibration to effect the orderly feeding of their contained splints to the supply chambers overlying the hopper. The troughs are vibrated in any suitable manner. In the present instance each trough is secured, as at 35, to the discharge end of a main splint supply trough 36 which is supported by spring standards 37 and is bodily vibrated with rapidity by the action of a power driven eccentric 38 against the limbs of a bifurcated bracket 39 depending from the trough 36. Splints supplied to the troughs 36 in any suitable manner are delivered therefrom to the upper portions of the inclined troughs 23, and the latter through their rapid vibration, feed the contained splints down to and within the enlarged chambers 22 of the troughs, whence they are discharged in good order into the hopper 12. During the vibrations of the two troughs the masses of splints overlying the hopper are moved against and from the inclined stationary walls afforded by the member 28, which walls thus impart a downward movement to the splints and cooperate with the curved portions 26 of the troughs to effect and insure the progressive and orderly delivery of the splints to the hopper.

I preferably pivot to the member 28 two oppositely extending bars 40 which over-

hang the respective troughs 23 and yieldingly rest upon the contained splints. These bars, thus bearing upon the underlying vibrating masses of splints, tend to compact them and prevent their working out of parallelism. The bars also serve as guards to prevent the overflowing of the splints from the troughs, and at the same time contribute to the efficient agitation and descent of the splints. 75

I do not limit my invention to the specific details herein disclosed as the same may be modified within the principle of the invention and the scope of the appended claims. 80

I claim--

1. In a match machine, the combination with a splint-inserting device and a hopper overlying the same, of two independent splint-feeding structures extending over said hopper from each end of the latter, and means for vibrating said structures longitudinally of the hopper, each of said structures comprising an upwardly and outwardly inclined chamber, means leading to the outer end wall of the chamber for supplying splints thereto, and a stationary member constituting the inclined inner end wall of said chamber. 90

2. In a match machine, the combination with a splint-inserting device and a vibratory hopper overlying the same, of two inclined troughs leading to the respective ends of the hopper and having extended side portions constituting the sides of independent splint-feeding chambers which overhang the hopper, stationary walls for the adjacent ends of said chambers, and means for vibrating said troughs. 95

3. In a match machine, the combination with a splint-inserting device and a vibratory hopper overlying the same, of two inclined troughs leading to the respective ends of the hopper and having extended side portions constituting the sides of independent splint-feeding chambers which overhang the hopper, stationary inclined walls for the adjacent ends of said chambers, and means for vibrating said troughs. 100 105

4. In a match machine, the combination with a splint-inserting device and a vibratory hopper overlying the same, of two inclined troughs leading to the respective ends of the hopper and having extended side portions constituting the sides of independent splint-feeding chambers which overhang the hopper, a stationary V-shaped member constituting inclined walls for the adjacent ends of said chambers, and means for vibrating said troughs. 110 115

5. In a match machine, the combination with a splint-inserting device and a vibratory hopper overlying the same, of two inclined troughs leading to the respective ends of the hopper and having extended and expanded side portions constituting the sides 120 125 130

of independent splint-feeding chambers which overlie the hopper, said troughs also having inclined bottom portions which lead to the ends of the hopper adjacent the respective troughs, stationary inclined walls for the adjacent ends of said chambers, and means for vibrating said troughs.

6. In a match machine, the combination with a splint-inserting device and a vibratory hopper overlying the same, of two inclined troughs leading to the respective ends of the hopper and having extended side portions constituting the sides of independent splint-feeding chambers which overhang the hopper, stationary inclined walls for the adjacent ends of said troughs, rods pivoted to said walls and longitudinally overhanging the respective troughs, and means for vibrating said troughs.

7. In a match machine, the combination with a splint-inserting device and a vibratory hopper overlying the same, of two inclined troughs leading to the respective ends of the hopper and having extended and expanded side portions constituting the sides of independent splint-feeding chambers which overlie the hopper, said troughs also having inclined portions which lead to the ends of the hopper adjacent the respective troughs, stationary inclined walls for the adjacent ends of said chambers, rods pivoted to said walls and longitudinally overhanging the respective troughs, and means for vibrating said troughs.

Signed at Barberton, in the county of Summit and State of Ohio, this 25th day of March, A. D. 1919.

MICHAEL PARIDON.
